LIGHTNING ARRESTER

Fritz Schröter, Berlin-Schmargendorf, Germany,
assignor to Radio Patents Corporation, New
York, N. Y.

Application April 5, 1929, Serial No. 352,695

8 Claims. (Cl. 250—27.5)

This invention refers to a type of lightning arrester applicable to power lines and particularly to high tension power lines. It is a well-known fact that the lightning surges in a high tension line consist of impulses of very short duration but of very considerable energy. Therefore, a device to discharge this energy to ground must possess the property of becoming a low resistance within a very small interval of time whenever the voltage exceeds a normal value. The glow discharge tube which comprises the type of lightning arrester which I have invented, is easily applicable in combination with condensers, a series of which may be connected from the high tension line to the ground and a set of glow discharge arresters, according to my invention, connected in series between the terminals of each of said condensers. In this way, the voltage of the line and the impulse voltage are subdivided between the condenser units and each of the glow discharge units will receive a different fraction of this voltage suitable for producing the desired action in this arrester.

The object of my invention is to secure an arrester giving a high tension potential and capable at the same time of carrying a high discharge current.

Another object of my invention is to produce an arrester which would respond within a very short interval of time, about one-thousandth of a second or less.

Another object of my invention is to produce a structure to withstand the heavy discharge of current.

35 Another object of my invention is to provide a method of securing an atmosphere within said arrester which is suitable for its proper function.

A further object of my invention is to provide a method of providing terminals within my arrester suitable for its function.

I have described my invention in reference to the accompanying figure, which shows a glow discharge tube with proper terminals and proper internal construction to accomplish the objects in view.

In this figure, 1 represents a glass vessel preferably of the kind known as pyrex glass or quartz which can withstand high temperature and high mechanical stress. The center portion of this vessel 2 is enlarged to receive a tubular helix 3 of high-melting point insulating material, such as pyrex glass or quartz. This helix is attached to the vessel 1 by means of a funnel 4, while the other end of this helix also shaped as a funnel, 55 may be supported by asbestos rings or any other

structure which would give a gas-tight separation between the upper and lower parts of the vessel.

I have mounted the terminals in the elongated upper and lower portions of vessel 1 as follows:—

A funnel of reduced diameter consisting of pyrex glass or quartz is sealed on to the vessel 1. Within said funnel, a copper or nickel lead 7 is mounted. This lead is sealed in the end of the vessel 1 and on the outside is attached to a metal cap 8 which is held to the end of the vessel by cement 9. The extreme end of the lead 7 carries an enlargement 10 which just clears the wall of the funnel 6 and to which is fastened the electrode 11, consisting of some high melting point metal such as tungsten, molybdenum, tantalum or some other similar material, especially those belonging to the 5A or 6A chemical group of the periodic table of Mandeléff as revised by Thompson. This metal electrode is surrounded by a shell of magnesium or some other material of the alkaline earth group or even an alloy of magnesium and aluminum. On the inside of this shell, I place a pressed compound consisting preferably of magnesium powder and barium oxide, but which may also be any other easily reducible material mixed with an oxide or salt of one or more metals, the latter being in each case, more electro-positive than magnesium. In other words, I may use the salt or oxide of any alkaline metal or earth alkaline metal such as the materials belonging to groups 1 and 2 of the periodic table of chemical elements (Mandeléff table as revised by Thompson). This mixture is prepared by mixing, say magnesium dust with barium oxide in proportion of .5 or .7 to 1, drying the mixture in vacuum and pressing it afterwards to a solid body under high pressure. The best way to do this is to press this material inside of the magnesium shell by means of a suitable pressing device while the tungsten or tantalum rod with the surface roughened, is held near the center. The electrode may be assembled in this manner and mounted on the lead 7 before sealing it into the vessel. The electrode is further treated after the tube is filled with gas in a manner described below:—

The atmosphere which may be used in this arrester, is preferably a rare gas, for example, a mixture of helium and neon at a pressure of from .1 millimeter to .5 millimeters of mercury. I have found that this gas will be more satisfactory for the purpose of securing high voltage than the argon on account of the fact that the length of my arrester is limited by the length of the con-

denser to which it is connected and that therefore, a gas with high internal resistance is necessary. The suggested mixture of gas will prevent occasional discharge at normal pressure. The windings of the discharge path through the helix increases the length of the discharge path and therefore, the potential to be applied to the tube before a discharge can occur in spite of the relatively short distance between the electrodes.

10 With this arrangement, I expect that the discharge may take place at about double the normal operating voltage.

After introducing helium and neon, I furthermore may admit a vapor of alkaline metal such as sodium or potassium or even of alkaline earth metal like barium. I may accomplish this through the filling tube 14 which is shown to have an enlarged portion 15 in which the metal to be vaporized 16 is inserted and heated by an external flame 17 during the process of filling. After admitting a sufficient quantity of such vapor, I seal the vessel at the point 18, removing the filling tube 14. However, with the construction of electrodes as described, I may use an alternative method of introducing the necessary alkaline metal vapor. The best way to accomplish this is to pass some strong discharge through the arrester after filling it with rare gas and sealing it off. This discharge should be of high voltage and power, during which metallic barium is formed around the hot electrodes by the chemical reaction of the barium oxide with magnesium, whereby barium vapors are formed which act to purify the inert gas and to decrease the cathode drop or in other words, to facilitate the formation of an arc in accordance with the function of these tubes.

Having thus fully described the construction and method of manufacture of my arrester, I wish it to be understood that I am not limited to the particular structure of the features of the method of preparation, except insofar as it is limited by the appended claims.

What I claim is:

45 1. A high voltage lightning arrester comprising a closed vessel, a gaseous atmosphere in said vessel, a first and second electrode for carrying a heavy discharge current, means consisting of a magnesium shell surrounding said first electrode and a mixture of reducible material containing electro-positive metal within said shell and in intimate contact with said first electrode.

50 2. A high voltage lightning arrester comprising a vessel of high melting point insulating material, filled with a gaseous atmosphere; a tubular helix of high melting point insulating material; a funnel for securing each end of said helix to the inside of said vessel; a pair of operating electrodes within said vessel arranged opposite one of said funnels each; funnel caps secured on the exterior of said vessel, and lead-in wires from said funnel caps to said electrodes.

55 3. A high voltage lightning arrester comprising a vessel of high melting point insulating material, filled with a gaseous atmosphere at reduced pressure, the central portion of said vessel being enlarged; a tubular helix of high melting point insulating material; a funnel for securing one end of said helix to the inside of said vessel, the opposite end of said helix being secured by a funnel; means for supporting said latter

funnel; a pair of electrodes within said vessel disposed opposite said funnels each; caps secured on the exterior of said vessel; and lead-in wires from said cap to said electrodes.

4. A high voltage lightning arrester comprising a vessel of high melting point material filled with an inert gas atmosphere; a helical tube of high melting point material mounted integral with and within said vessel to produce two separate compartments communicating through said tube; a pair of electrodes within said vessel disposed opposite the openings of said tube; a shell of electro-positive material within said vessel containing electro-positive metal in intimate contact with said electrodes.

5 5. A high voltage lightning arrester comprising a vessel of high melting point material filled with an inert gas atmosphere; a pair of metal electrodes disposed within said vessel; means for extending the discharge path between said electrodes comprising a helically wound tube of high melting point material mounted within and integral with said vessel with its openings opposite said electrodes; a shell of magnesium surrounding said electrodes; and a compressed mixture of reducible material containing electro-positive substance within said shell in intimate contact with said electrodes.

10 6. A protective device for high voltage electric circuits comprising a vessel of high melting point material filled with a gaseous atmosphere at reduced pressure; electrodes disposed within said vessel to provide an elongated discharge path therebetween for increasing the operating voltage of said device; and a supply of electro-positive material within said vessel in intimate contact with said electrodes for producing purifying vapors through heating by said electrodes upon the occurrence of a discharge.

15 7. A protective device for high voltage electric systems comprising a vessel of high melting point material filled with an inert gas atmosphere at reduced pressure; electrodes disposed within said vessel; means for extending the discharge path between said electrodes for increasing the operating voltage of said device comprising a convoluted tube of high melting point material mounted within said vessel with its openings disposed adjacent to said electrodes and a supply of reducible material containing electro-positive substance in intimate contact with said electrodes for producing purifying vapors through heating by said electrodes upon the occurrence of a discharge.

20 8. A protective device for high voltage electric systems comprising a vessel of high melting point material filled with an inert gas atmosphere at reduced pressure; a pair of electrodes disposed within said vessel; means for extending the discharge path between said electrodes to increase the operating voltage of said device comprising a convoluted tube mounted integrally with and inside of said tube with its openings adjacent to said electrodes; a shell of electro-positive material surrounding said electrodes and a compressed mixture of reducible material containing electro-positive substance within said shell and in intimate contact with said electrodes for producing purifying vapors through heating by said electrodes upon the occurrence of a discharge.
